UNITED STATES PATENT OFFICE

138,565

DESIGN FOR A TOY PHONOGRAPH

James E. Adair, Chicago, Ill., assignor to Color-graphic, Inc., a corporation of Indiana

Application May 17, 1944, Serial No. 113,623

Term of patent 14 years

(Cl. D34—15)

To all whom it may concern:

Be it known that I, James E. Adair, a citizen of the United States, residing at Chicago, in the county of Cook and State of Illinois, have invented a new, original, and ornamental Design for a Toy Phonograph, of which the following is a specification, reference being had to the accompanying drawings, forming part thereof.

Figure 1 is a plan view of a toy phonograph, showing my new design;

Figure 2 is a side elevation of the toy phonograph shown in Figure 1;

Figure 3 is a side elevation at right angles to that of Figure 2; and

Figure 4 is a bottom view.

I claim:

The ornamental design for a toy phonograph, as shown.

JAMES E. ADAIR.
